Williamson Peirce Williamson

UNITED STATES PATENT OFFICE

ROBERT W. JOHNSON, OF MINNEAPOLIS, MINNESOTA

JOURNAL BOX PACKING RETAINER

Application filed March 28, 1930. Serial No. 439,709.

This invention relates to railway journal boxes and especially to means associated therewith for retaining the waste or other packing in proper position against the lower portion of the journal.

At the present time, all journal boxes on railway cars have to be inspected often and re-packed to prevent the waste or other absorbent material which carries the oil or lubricant from becoming displaced from the journals. The rapid rotation of the journal in a short time loosens the packing, throwing it upwardly and also outwardly against the lid of the box. If lubrication is removed from the journal, a hot box will occur after a few miles travel.

It is an object of my invention to provide a simple but highly efficient journal box packing retainer, which will positively prevent the waste or other packing material from becoming displaced from the journal, which may be readily installed in standard forms of journal boxes now extensively used, at comparatively low cost, and which will comply with railroad requirements.

It is a further object to provide a packing retainer of the class described, wherein the waste or packing may be readily inspected and replenished without removal of the device from the journal box.

More specifically it is an object of my invention to provide an efficient journal box packing retainer, which will both prevent the waste or packing material from being moved forwardly and outwardly from the journal and upwardly between the journal and the sides of the box.

These and other objects and advantages of the invention will be fully set forth in the following description made in connection with the accompanying drawing wherein like reference characters refer to similar parts throughout the several views and wherein,

Fig. 1 is a view mostly in vertical section taken longitudinally of a common type of journal box extensively used at this time having incorporated therein an embodiment of my invention;

Fig. 2 is a horizontal section taken on the line 2—2 of Fig. 1;

Fig. 3 is a cross section taken on the line 3—3 of Fig. 1;

Fig. 4 is a cross section of the hinged retaining plate detached; and

Fig. 5 is a fragmentary section taken on the line 5—5 of Fig. 4, showing the manner in which the end bolts are mounted in the hinged plate for engagement with the retaining flange.

As shown in the drawing, the journal box, indicated as an entirety by the numeral 6, is provided with the usual doorway at the upper portion of the outer end, said doorway being closed by the lid 7, which is pivoted by pins 7a to the usual pivot ears usually formed integrally with the box. The wheel axle is indicated by the letter A having the journal portion 8 mounted within the box and terminating in the enlarged journal end or flange 8a disposed a short distance inwardly of the box lid 7. The journal bearing 9 is mounted in the upper portion of the box and held in place by the usual key 10.

Packing P, usually in the form of waste or other absorbent material, impregnated with oil or suitable lubricating material, is stuffed beneath and around the lower portion of the journal and the outer end 8a thereof.

My packing retainer comprises a pair of elongated flanges or strips 11 secured to the opposing vertical inner walls of the box and preferably declined somewhat, the inwardly projecting longitudinal edges of said flanges being downturned and disposed in close spaced relation with the journal 8. Flanges 11 may be independent elements secured by suitable means, such as bolts 12 to the walls of the box, or, if desired, may be integrally pressed or cast with the box. The outer ends of flanges 11 preferably have cut out portions 11a which are adapted to accommodate the flanged or enlarged end 8a of the journal, as clearly shown in Fig. 2.

Between the lower edge of the journal box doorway and the end 8a of the journal, I mount a retaining plate 13, which preferably extends substantially horizontally and has its inner longitudinal edge disposed in close relation to the end 8a of the journal. Plate 13 is preferably detachably hinged to

the opposite vertical sides of the box and to this end, may be provided with a fixed trunnion 14, which is pivoted in a suitable socket or recess in one of the journal box walls, 5 while at the other end of the plate a longitudinally slideable trunnion or bolt 15 is provided, which may be telescoped in a rolled or tubular portion 13a of plate 13, said tubular portion being disposed in the outer longitudinal edge of the plate. Bolt 15, as shown, 10 is yieldingly held in outward position by a coiled spring 15b mounted within the tube 13a and a laterally extending pin 15a secured to bolt 15 may work through a suitable slot in the tube 13a to facilitate release of bolt 15 from engagement with a socket or aperture in one of the vertical sides of the box.

The ends of plate 13 may be rolled or otherwise formed to provide transversely extending sleeves 13b in which spring pressed bolts 16 are mounted, said bolts being yieldingly projected by springs 16b to engage below the ends of the retaining flanges 11. The bolts 16 may have beveled ends in order that they 25 may be cammed inwardly by the downward swinging movement of the retaining plate 13, thereby automatically interlocking with the ends of flanges 11. The bolts are also provided with lateral pins or handles 16a 30 working in suitable transverse slots formed in the ends of plate 13 to permit the bolts to be manually withdrawn when it is desired to release the hinged plate for upward swinging movement.

35 It will be readily seen that with my device, it will be impossible for the packing material to work upwardly around the top of the journal during the travel of the railway cars, since it is effectively obstructed by the 40 flanges 11 and it will also be seen that the packing cannot be worked outwardly toward the doorway and lid of the journal box, since the hinged retaining plate 13 locked in operative position by cooperation with the forward ends of flanges 11 completely obstructs 45 displacement of material between the end of the journal and the forward or outer end of the journal box.

To inspect the packing and to replenish 50 the same, it is only necessary to raise the lid 7, release bolts 16 from engagement with the flanges 11 and swing the retaining plate upwardly and outwardly into substantially horizontal position upon the lower edge of the 55 doorway. The packing can then be clearly viewed, inspected, and if necessary replenished without removing the retaining plate or other elements of my retaining device. It will be obvious that the flanges 11 will 60 not interfere with the efficient packing of the box.

After inspection or replenishment of the packing, the hinged retaining plate 13 may be merely swung inwardly and downwardly 65 with sufficient force to cause the bolts 16 to

be cammed into locking engagement beneath the ends of flanges 11.

The hinged retaining plate 13 is so constructed that it may be quickly and easily removed from the journal box (although this 70 is seldom necessary) by releasing the bolt 15 and slipping the trunnion 14 from engagement with its socket. The plate may then be lifted through the doorway.

From the foregoing description, it will be 75 seen that I have invented a simple but highly efficient journal box packing retainer adapted to be installed in standard journal boxes utilized extensively at this time at little cost and for filling all requirements of the railroads insofar as inspection and servicing of 80 the journal boxes and packing are concerned.

It will, of course, be understood that various changes may be made in the form, details, arrangement and proportions of the 85 parts without departing from the scope of my invention, which, generally stated, consists in a device capable of carrying out the objects above set forth, in the novel parts and combinations of parts disclosed and defined in the appended claims.

What is claimed is:

1. In combination with a journal box and a journal disposed therein, a packing retainer comprising a pair of inwardly projecting flanges mounted within said box and extending longitudinally of the side walls thereof between the same and the journal, said flanges terminating at their outer ends adjacent the end of the journal, and a hinged retaining plate disposed within the box between the doorway and the end of the journal and means engagable with the outer ends of said flanges for retaining said hinged plate against upward displacement.

2. In combination with a journal box and a journal disposed therein, a packing retainer comprising a plate mounted transversely within the box and extending between the lower edge of the doorway and the end of the journal, means associated with the inner longitudinal edge of said plate for retaining said plate against upward displacement and hinge elements at the outer longitudinal edge of said plate, at least one thereof being releasable to permit detachment of said plate from the box.

3. A waste retainer for journal boxes having in combination, a pair of strips extending longitudinally of the journal above the packing or waste and traversing the space between the side walls of the box and the journal and terminating substantially flush with the end of the journal and a substantially horizontal retaining plate disposed within the box traversing the space between the doorway and the end of the journal and hinged at its outer edge for upward swinging movement to permit inspection of the waste or packing and means for retaining 130

said hinged plate against upward displacement.

4. A waste retainer for journal boxes having in combination a pair of strips extending longitudinally of the journal above the packing and waste and traversing substantially the entire space between the side walls of the journal box and the periphery of the journal including the flanged end of the journal, said strips terminating substantially flush with the end of the journal and a substantially horizontal retaining plate disposed within the journal box and hinged along one of its longitudinal edges on an axis adjacent the lower edge of the doorway of the box, said plate being constructed to swing upwardly and outwardly through the doorway of the box and traversing, when in operative position, substantially the entire space between the forward end of the box and the end of the journal and outer ends of the strips, and means for retaining the free edge of said plate against upward displacement.

In testimony whereof I affix my signature.

ROBERT W. JOHNSON.
